UNITED STATES PATENT OFFICE.

AMOS A. SOUTHWICK, OF ASHTABULA, OHIO.

DESIGN FOR A BADGE.

SPECIFICATION forming part of Design No. 18,609, dated September 11, 1888.

Application filed August 2, 1888. Serial No. 281,819. Term of patent 7 years.

To all whom it may concern:

Be it known that I, AMOS A. SOUTHWICK, a citizen of the United States, residing at Ashtabula, in the county of Ashtabula and State 5 of Ohio, have invented and produced a new and original Design for Badges; and I do declare the following to be a full, clear, and exact description of the same, reference being had to the accompanying drawings, forming a 10 part thereof, and in which—

Figure 1 is an elevation of one side of a campaign-badge showing my design, and Fig. 2 is a similar elevation taken from the reverse side of the badge.

15 The leading feature of my design consists of the representation of a coat or an overcoat with a ribbon above said coat.

In the drawings, A is the body of the coat,

having a band, a, at its upper end, and B B' the two sleeves extending at an angle from opposite sides of said body near the upper end. 20

C is the ribbon, which is connected to a raised strap, D, (seen in Fig. 2.) This ribbon is represented as tied into a bow, as shown.

What I claim is—

25 The design for a campaign-badge herein shown and described, comprising the representation of a coat, A, a raised strap, D, within the collar of the coat, and a ribbon, C, passing beneath the strap, as set forth.

30 In testimony whereof I affix my signature in presence of two witnesses.

AMOS A. SOUTHWICK.

Witnesses:

C. F. KEPLER,
M. E. SOUTHWICK.
